UNITED STATES PATENT OFFICE.

SCHUYLER H. EARL, OF ROCHESTER, NEW YORK, ASSIGNOR TO GLEASON WORKS, OF ROCHESTER, NEW YORK, A CORPORATION OF NEW YORK.

LUBRICATING MECHANISM FOR GEAR-CUTTING MACHINES.

Application filed October 4, 1924. Serial No. 741,583.

To all whom it may concern:

Be it known that I, SCHUYLER H. EARL, a citizen of the United States of America, residing at Rochester, in the county of Monroe and State of New York, have invented a certain new and useful Improvement in Lubricating Mechanism for Gear-Cutting Machines, of which the following is a specification.

10 This invention relates to lubricating systems, especially such as are adapted for use on gear cutting machines and more particularly relates to a lubricating system in which those movements of the machine required in 15 obtaining the desired tooth form are employed to effect lubrication of the moving parts.

In machines of this general type, it has, heretofore, been impractical to effect the 20 automatic lubrication of all the moving parts and for such parts as can not be lubricated oil cups are generally provided which it is intended shall be periodically refilled by the operator. The refilling of such cups is 25 often neglected, however, with injurious effects to the parts moving without lubrication.

The primary object of my invention, then, 30 is to provide mechanism which may be used alone or in conjunction with other mechanism to render possible full automatic lubrication of the machine; and a further purpose is to provide lubricating mechanism which will be characterized by a minimum of parts, which 35 will be simple and efficient in operation, and of the requisite strength.

A particular embodiment of the invention is described in the following specification and illustrated in the accompanying drawings, it being specifically understood, however, that my invention is not restricted to the particular mechanism illustrated and described, but is capable of modification within the scope of the invention and within 45 the limits of the accompanying claims.

In the drawings:—

Figure 1 is a plan view, with the parts broken away, of a gear cutting machine, equipped with the lubricating mechanism of 50 my invention;

Fig. 2 is a section on the line 2—2 of Fig.

Fig. 3 is an end elevation of the index head with the cover removed;

Fig. 4 is a section on the line 4—4 of Fig. 1;

Fig. 5 is a detail;

Fig. 6 is an enlarged detail view of the bearing face of the cradle; and

Fig. 7 is an enlarged detail of the end face of the cradle.

While the invention is applicable to gear cutting machines of various types, involving different forms of tool mechanism and employing different relative motions between the tool and blank to obtain the desired tooth form, it is particularly pertinent to machinery in which the gear blank partakes of both a rotary motion about its own axis as well as a bodily movement so as to roll the blank on the tool during the cutting operation in 70 the manner of a blank rolling on a crown gear, and it is in connection with such a machine that the invention is herein illustrated and described.

Referring to the drawings by numerals of reference, I have shown a gear cutting machine provided with a frame 1 on which is slidably mounted the tool head 2 carrying a planer tool 3. At one end the frame is provided with an upright portion 4 in which 80 a cradle 5 oscillates. The means for oscillating the cradle may be of any desired form. As shown, a lever 6 is employed, which is pivoted at one end to the frame and at its other end to an extensible link 7; and is 85 provided intermediate its ends with a roller 8 which travels in the groove of a cam 9. Movements of the lever 6 serve, through the lever 7 and link 10, to oscillate the cradle.

The frame portion 4 is provided with a reservoir 11 which contains a lubricant and with a bore 12 communicating with the reservoir and adapted to conduct the lubricant from the reservoir to the ways on which the cradle oscillates. The reservoir 11 may 95 be periodically filled by the operator or preferably will be kept at a constant level by the pumping mechanism usually employed in machines of the character described.

The bearing faces 13 of the cradle which 100 ways in the frame portion 4 are

formed with V-shaped grooves which serve to distribute the lubricant over said faces and the cradle itself is formed with a bore 14 adapted to register with the bore 12 in predetermined positions of the cradle movements and to conduct lubricant from the reservoir to the parts carried by the cradle.

10 Mounted on the cradle, in the embodiment of the invention illustrated, is the base 15 which is adjustable on the cradle and which may be secured in any adjusted position thereon by means of T bolts which are engaged in grooves 16 of the cradle. Rotatably mounted on the base is a sleeve 17 to 15 which is attached the gear segment 18 which is adapted to roll on a gear segment 19, which is secured to the frame. The gear blank 20 is mounted on a spindle 21 which is normally locked to the sleeve 17, but 20 which is capable of rotating relatively to such sleeve. The movement of the cradle will cause rotation of the spindle 21 about its axis, so that the gear blank is given a combined movement in the manner of a 25 blank rolling upon a crown gear, as is common in this art.

A flexible tube 22 serves to conduct the lubricant from the bore 14 to the parts mounted upon the cradle. Difficulty heretofore has been experienced in lubricating certain of the cradle parts, such as the indexing mechanism, because there was not sufficient pressure to carry the oil to these parts against the action of gravity. To 30 overcome this difficulty, I propose to provide the machine with suitable mechanism for automatically pumping the oil conducted to the cradle to those parts and actuate said automatic mechanism by the movements of 35 the parts themselves.

As shown, the lubricant is conducted from the tube 22 through the bore 23 whence it serves to lubricate the sleeve 17 and from the bore 23 through the bore 24 to bore 25 40 formed in a plate 26, which is adjustably secured to the base 15, whence it is conducted through a bore 27 to a pocket or reservoir 28 which is aligned with a bore 29 in which reciprocates a plunger 30. A one-way valve 50 comprising the ball 31 normally closes the pocket 28. This valve is opened on the up-stroke of the plunger by suction and the oil drawn from the pocket into the chamber 32. On the down-stroke of the plunger, ball 31 55 is closed and the oil forced from the chamber 32 through the bore 33 and the pipe 34 to the upper part of the cradle, whence it is distributed by gravity from the discharge pipe 35 over the indexing parts. A one-way valve comprising the ball 36 serves to 60 prevent any of the oil from running back through the bore 33 into the chamber 32.

For actuating the plunger, I preferably employ means adapted to be operated by 65 movement of the parts of the cradle. In the

embodiment of the invention shown, this means includes a lever 37 secured to a rock shaft 38, to which is connected at one end a lever 39 having a slot-and-pin connection 40 with the plunger 30. The lever 37 is actuated once in each roll of the blank by contact of the lever 41 therewith. This lever 41 forms a part of the indexing mechanism of the machine and is mounted on an arm 42 which is carried by the sleeve 17 and serves 75 normally to lock the blank spindle to the sleeve so that the sleeve and spindle rotate together.

While I have chosen preferably a portion 80 of the indexing mechanism to actuate the pump, the particular indexing mechanism itself forms no part of my invention. This mechanism is similar to that described in the co-pending application of James E. Gleason, George H. Bryan, Eyvind Finsen and Alton P. Slade, Serial No. 715,390, filed May 23, 1924, and reference may be had to such application for a more detailed description thereof.

For a ready understanding of the working 90 of this mechanism, however, a brief description is given here:

The lever 41 which is mounted on the arm 95 42 carried by the sleeve 17 to which is keyed the gear segment 18. This lever 41 is provided with a dog 43 which engages selectively notches in the index plate 44, which is secured to the blank spindle 21. A spring-pressed plunger 45 serves to normally 100 retain the dog 43 in engagement with the notch in the index plate, thus normally locking the spindle to the sleeve so as to rotate therewith.

During the turning movement of the 105 sleeve 17 caused by the rotation of the segment 18 on the stationary segment 19, the tail piece of the lever 41 will engage a relatively stationary abutment 46 and thus cause the rear end of the lever to be depressed, moving the dog 43 out of engagement with the index plate. Further movement of the arm 42 causes the segment 47 to engage a stationary tooth 48, thus rocking the segment 47 and the rock shaft 49 to which the segment 47 is secured. A second segment 50 110 is attached to the same rock shaft and engages and turns the segment 51 on the collar 52 which carries a pawl 53 so that, as the collar 52 rotates, the pawl 53 engages the ratchet wheel 57 secured to the blank spindle 115 and rotates the same one tooth space. A spring 54 normally moves the pawl 53 into operative position and a cam surface 55 on the lever 41 engages a roller 56 carried by 120 one end of the pawl to hold the pawl out of operative position during cutting against action of the spring.

As will be obvious from the description given, as the cradle 5 oscillates oil is conducted from the reservoir 11 in the frame 125

to the pocket 28 in the plate 26, whence it is pumped by the plunger 30 actuated at predetermined intervals by the rolling movement of the blank support, the lever 41 when it reaches a predetermined position moving the lever 37 and through such lever the plunger to raise the oil into the chamber 32. The plunger is returned to normal position to force the oil from the chamber 32 by gravity, though if desired a spring or any suitable mechanical means may be attached for this purpose to the levers 37 and 39 or directly to the plunger itself.

While I have illustrated a particular embodiment of the invention, it is to be understood that I do not desire to be restricted to the specific mechanism shown as the improvements for forcing the oil to the moving parts may be of any desired type within the limits of my invention, and as said improvements may be controlled automatically by movement of any of the machine parts in the operation of the machine. So while I have shown and described my invention as applied to gear cutting machines of the generating type, in which a planer tool is employed, it is to be understood that the invention may be used on other types of generating machines and in some aspects on machines of the non-generating type also, and that the tool mechanism may involve a grinding member or any other suitable type of cutter.

Moreover, where the invention is employed on machines of the generating type, it is to be understood that either the tool or the blank may partake wholly of the generating roll or that the roll may, in part, be applied to each.

40 I claim:—

1. In a machine of the class described, the combination with tool and gear blank supports, means for rolling the tool and blank relatively to each other to produce a generated tooth profile, lubricating mechanism, and devices whereby said relative rolling movement automatically effects operation of the lubricating mechanism at predetermined intervals.

50 2. In a machine for producing gears, the combination with tool and gear blank supports, of a movable bed on which one of said supports is mounted, means adapted to move said support relative to the bed on movement of said bed, lubricating mechanism including means whereby the relative movement between the blank support and movable bed affords power for forcing the lubricant to said support at predetermined intervals.

60 3. In a machine for producing gears, the combination with tool and gear blank supports, of a movable bed on which one of said supports is mounted, means adapted to rotate said support on movement of said bed,

lubricating mechanism, and devices carried partially by said support and partially by said movable bed and acting to positively and automatically effect lubrication of the parts of the machine when the movable bed reaches a predetermined position.

4. In a machine for producing gears, the combination with tool and gear blank supports, of a movable bed on which one of said supports is mounted, means adapted to 75 rotate said support on movement of said bed, lubricating mechanism, and devices carried partially by said support and partially by the movable bed and acting to positively and automatically effect lubrication of the 80 parts of the machine when said support reaches a predetermined position.

5. In a machine for producing gears, the combination with tool and gear blank supports, of a movable bed on which one of 85 said supports is mounted, means for moving said support on movement of said bed, lubricating mechanism, and devices adapted to be actuated by the means for moving the support to positively and automatically 90 effect lubrication of the machine at predetermined intervals.

6. In a machine of the class described, the combination with tool mechanism, of a gear blank support, a movable bed, on which the blank support is mounted, means adapted to rotate said support on movement of the bed, lubricating mechanism, indexing mechanism for the blank support, and cooperating devices carried by the indexing mechanism 100 and bed and adapted to effect lubrication of the support at predetermined intervals.

7. In a machine of the class described, the combination with a frame provided with a reservoir, of a bed movable in the frame and a support mounted on said bed, of means on the bed adapted on movement of the bed in one direction to conduct a lubricant from said reservoir to a second reservoir carried by the bed, means for rotating said support 110 on movement of said bed, and devices whereby rotation of said support automatically affords the power to force the lubricant from said second reservoir at a predetermined position in the movement of said bed. 115

8. In a machine of the class described, the combination with a frame provided with a reservoir, tool and gear blank supports, a bed movably mounted on the frame and adapted to carry one of said supports, means for rotating said support, means adapted on movement of said bed in one direction to conduct lubricant from said reservoir to a second reservoir, indexing mechanism for said support, and cooperating devices carried by the indexing mechanism and the bed operating to automatically force a lubricant from the second reservoir to the machine parts at predetermined intervals. 125

9. In a machine of the class described, the 120

combination with tool mechanism and a support therefor, of a gear blank support and a bed on which one of said supports is mounted, lubricating mechanism carried by said bed, means for moving the support relatively to the bed, a spindle rotatably mounted on the support, means for locking the spindle and support so as to normally move

together, means for releasing said locking means to permit indexing of the spindle, and cooperating devices on said locking means and bed adapted at predetermined intervals to actuate said lubricating mechanism.

In witness, whereof, I have hereunto set my signature.

SCHUYLER H. EARL.
